2,260,554

METHOD OF CUTTING STENCILS

Donald L. Boyd, Huntington, W. Va., assignor to
Carb-O-Spot Corporation, Athens, Ohio, a cor-
poration of Ohio

Original application March 6, 1940, Serial No.
322,456. Divided and this application October
15, 1940, Serial No. 361,215

4 Claims. (Cl. 164—125)

My invention relates more specifically to printing presses of the type described in my copending application Serial No. 322,456, filed March 6, 1940 of which this is a division.

That application describes a printing press designed to print spots of wax carbon on sheets of paper through a belt stencil. The forms on which the spots are printed are superimposed on other forms having spots of wax carbon printed in various other locations.

The object is to produce a form which although to top sheet will contain a complete record of the entire transaction, only parts thereof will be transferred to the other sheets.

It will be seen from this brief description that it is of vital importance that the spots are printed so as to ensure accurate registration of the spots with the desired locations or the forms will be worthless. In the application referred to above the paper is passed over an impression cylinder, and between it and a belt stencil. In the stencil are cut apertures of the various designs for the differently located spots. Adjacent the edges of the belt stencil I provide a series of perforations or notches adapted to register with toothed wheels and in this manner I can obtain exact registration, and turn out an accurate piece of work.

It will be obvious from the foregoing that an essential part of the stencil is to have the notches or perforations adjacent the edge correctly located in relation to the design to be cut in the stencil.

My invention has for its principal object to provide means for cutting stencils which will ensure correct registration when the stencil is put to use on press.

My means for accomplishing the foregoing objects may be more readily understood by having reference to the accompanying drawing, in which:

Fig. 1 is a perspective view of my improved means for cutting a stencil;

Fig. 2 is a detail view of the stencil without the design;

Fig. 3 is a detail view of the face of the female portion of the cutting die;

Fig. 4 is an edge view of the male portion of the cutting die; and

Fig. 5 is a modified detail view of a stencil.

Similar reference numerals refer to similar parts throughout the entire specification.

As shown in the drawing, a cutting die 1, is provided with a punch 2 of the desired configuration. The female part 3 of the die, which is 55

adapted to receive the punch 2, is combined with a template comprising a plurality of teeth 4, adapted to fit the perforations or notches 5, as the case may be which are punched adjacent or cut in the edges of the stencil. The design or central area and side perforations may be simultaneously formed to prevent errors due to shrinkage in the stencil. These perforations 5 may be stamped or punched in the stencil 6, by means of a cutting or stamping die of ordinary construction. As illustrated it comprises a male portion 7, and punches 8 corresponding to perforations 5, and the female portion 9.

A plurality of teeth 4 which correspond to the perforations 5 in the edge of the stencil 6 are formed adjacent the edge of the female part 3 of the main die 1. I have shown perforations adjacent the edges of the stencil, it will be obvious that these may be notches cut in the edges of the stencil instead of perforations.

The operation is as follows, the cutting die 1, is placed in a suitable press and the perforations or notches cut in the stencil paper. Preferably these perforations or notches should be one half inch from center to center, as that is found to be most practical for the reason that most commercial work is in multiples of such units. The stencil paper is then placed on the female part of the die 1, and the perforations or notches 5 are fitted to the teeth 4, this serves to hold the stencil paper in position while apertures of the required design are being punched.

The cutting die 1 is then locked in position on a suitable press (not shown), and the press is started cutting the first design 10. The stencil 6 is then moved forward the required number of punches and again fitted to the teeth 4, and the press is once more started, making the second design. This is repeated until the entire belt has been cut with the requisite number of designs.

I have shown a certain design, but this is because it is a design which I have printed on a quantity of tax forms. It should however, be obvious that any desired design for the spots to be printed may be cut accurately provided the notches 5 are first punched in the stencil 6, and a template having coinciding teeth is fastened to the female part 3 of the die 1.

Having described my invention, what I regard as new and desire to secure by Letters Patent is:

1. The method of cutting a stencil comprising the following steps; forming a plurality of perforations having each one line as a side to establish direction in stencil paper, preparing a template having a plurality of teeth, which are fit-

ted to and coincide with said perforations, and then cutting out predetermined areas from said stencil while it is held by said template.

2. The method of cutting a belt stencil comprising the following steps; forming a plurality of perforations in stencil paper, preparing a template having a plurality of teeth, which are fitted to and coincide with said perforations and then simultaneously cutting out predetermined areas from said stencil while it is held by said template.

3. The method of cutting a belt stencil comprising the following steps; forming a plurality of perforations in stencil paper adjacent the edge and on one half inch centers, preparing a

template having a plurality of teeth, which are fitted to and coincide with said perforations and then cutting out predetermined areas from said stencil while it is held by said template.

4. The method of cutting a belt stencil comprising the following steps; forming a plurality of notches in edges of the stencil paper and on one half inch centers, preparing a template having a plurality of teeth, which are fitted to and coincide with said notches and then cutting out predetermined areas from said stencil while it is held by said template.

DONALD L. BOYD.
